EXPANSION RAIL JOINT

Herbert Secor Clarke, Albany, N. Y., assignor to
 Ramapo Ajax Corporation, New York, N. Y., a
 corporation of New York

Application July 29, 1935, Serial No. 33,715

9 Claims. (Cl. 238—171)

The invention relates in general to railway track equipment, and more particularly to expansion joints for taking care of considerable relative longitudinal movements between adjoining sections of track. Such expansion joints are used, for example, at the ends of long bridges and at the ends of long sections of welded track and also at other locations where there is likely to be considerable creepage of the rail due to 5 temperature changes or other causes.

According to a preferred embodiment of the invention, the expansion joint comprises a point rail and a stock rail resting upon a sliding plate which in turn rests upon a base plate supported by the ties. The point rail may be fixedly secured to the sliding plate and the stock rail may be slidably mounted in a guideway secured to the sliding plate. The guideway is arranged to hold the body of the stock rail along the 10 same gauge line as the point rail, while the end of the stock rail is flexed laterally out of said gauge line, slidably resting against the outer face of the point rail.

Thus, either rail is free to move a considerable 15 distance in either direction relative to the road bed and the rails are free to move relative to each other. The arrangement is such that the gauge of the track at all points along the expansion joint remains constant and continuous. 20 support along the expansion joint is obtained for the rolling stock in all positions of adjustment of the joint.

The invention also consists in certain new and 25 original features of construction and combinations of parts hereinafter set forth and claimed.

Although the novel features which are believed to be characteristic of this invention will 30 be particularly pointed out in the claims appended hereto, the invention itself, as to its objects 35 and advantages, and the manner in which it may be carried out, may be better understood by referring to the following description taken in connection with the accompanying drawings forming a part thereof, in which—

Fig. 1 is a plan view of the expansion joint; 40 Fig. 2—6, inclusive, are sections taken along the lines 2—2, 3—3, 4—4, 5—5 and 6—6, respectively, illustrating the construction at various points along the length of the expansion 45 joint.

In the following description and in the claims, 50 various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings, the conventional wooden railway ties are indicated by 10, these ties supporting a base plate 11 held down by screw bolts 12 in a manner well known in the art. Mounted on the base plate 11 is a sliding plate 13 held in position on its longitudinal edges by a longer guide 14 and a shorter guide 15. The guides 14 and 15 have overhanging flanges disposed over the sliding plate 13 and are secured to the base plate by a series of bolts 16.

For permitting the sliding plate 13 to easily slide on the base plate 11, the former is provided with a network of intersecting grease grooves 18 which communicate with a series of high pressure grease fittings screwed into the upper 20 surface of the sliding plate 13 by which the plates may be lubricated with a suitable high pressure grease gun. The high pressure grease fittings have been omitted, and the network of grease grooves has not been illustrated in Fig. 30 1, for purposes of simplicity of illustration.

If desired, the expansion joint may be tipped slightly toward the other rail of the track. For this purpose, inclined seats may be cut in the top surface of the ties 10 sloping from the lowest 35 part of the seat, indicated by 19, upwardly and outwardly toward the end of the ties at an angle to horizontal, of, say, 1 in 40 to 1 in 20, as may be desired.

The point rail 20 is made from a standard T- 40 rail. It is bent inwardly at the pointed end of the rail and has its head 24 planed along its gauge side to provide uniform track gauge. The outer side of the head 24 and base flange 23 opposite the gauge side is machined away, as illustrated especially in Figs. 3 and 4, to provide a generally curved surface to ride against the fixed end of the relatively movable stock rail 26.

It will be noted particularly from Fig. 3 that the web 21 directly underlies the head 24 at the 45 extreme tip 22 of the point rail 20. It will be, furthermore, noted from Fig. 3 that the top surface of the tip 22 is machined to lie below the top surface of the stock rail 26 and that the top surface of the head 24 gradually slopes up- 50 55

wardly away from the tip 22 through the position shown in Fig. 4, thence to the normal un-machined top even with the top surface of stock rail 26, as indicated in Fig. 5.

- 5 The point rail 20 seats in a recessed seat 37 in the sliding plate 13 and is rigidly secured to the sliding plate 13 by a flange brace 30, auxiliary braces 31 and 32 and a tip brace 33. The flange brace 30 overlies the base flange 23 10 and is secured to the sliding plate 13 by suitable bolts, as indicated in Fig. 1.

Referring to Fig. 5, the auxiliary brace 31 is suitably webbed for strength and is bolted to the sliding plate 13 by bolts 34 and snugly engages 15 the fishing surfaces on the head 24 and flange 23 as indicated. A series of bolts 36 bolt the auxiliary brace 31 and a spacer block 35 to the point rail 20. It will be noted especially 20 from Fig. 1 that the top surface of spacer block 20 35, remote from the tip 22, is beveled.

Referring to Fig. 4, the auxiliary brace 32, similar in construction to brace 31, is bolted to the sliding plate 13 by bolts 34 and is bolted to the point rail 20 and to a filler block 38 by 25 bolts 39.

Referring to Fig. 3, the tip brace 33 has two sections, one rigidly secured to the point rail and the other slidably engaging the stock rail 26. The tip brace is rigidly secured to the sliding plate 13 by bolts 34 and the one section is secured to the point rail 20 and to the filler block 38 by bolts 39.

The stock rail 26 is also a standard T-rail having its head 42 undercut, as at 43, all the way along from the point 46 to the end of the rail to permit making the tip 22 of the point rail heavier than would be possible were the head 42 not undercut. The flange 44 of the stock rail 26 slidably rests in the seat 37 of the sliding plate 13 and is cut away on its inner side from the point 46 all the way to the end of the rail to fit the machined surface on the point rail 20. The extreme end of the stock rail 26 is machined off as indicated by 45.

45 The stock rail 26 is flexible laterally and is slidably lengthwise between the point rail 20 and the filler blocks 35 and 38, tip brace 33 and auxiliary brace 47 on the one hand, and main brace 48 and auxiliary braces 49 and 50 on the other hand.

50 The main brace 48 (Fig. 3) is suitably webbed for strength and is rigidly secured to the sliding plate 13 by bolts 51 and slidably engages the fishing surfaces of stock rail 26, as indicated in Fig. 3.

The auxiliary braces 47 and 50 (Fig. 2) are also suitably webbed for strength and are secured to the sliding plate 13 by bolts 51 and also slidably engage the fishing surfaces of the stock rail 26. Auxiliary brace 49 is similar in construction to auxiliary brace 50 and also is rigidly secured to the sliding plate 13 and slidably engages the fishing surfaces of the stock rail 26.

65 If desired, the sections rigidly secured together may be reenforced by welding. Welding 60 may be provided between the outer way 15 and the base plate 11. If desired, the welding may be omitted on the corresponding inner way 14 which does not have to withstand as much stress as the outer way 15. Also welding 61, 62 and 63 may be provided between the braces 31, 32 and 33 and the sliding plate 13 as indicated. Also welding, indicated by 64 and 65, may be 70 provided between the point rail 20 and the

sliding plate 13. Also welding 66 and 67 may be provided between the filler block 38 (Figs. 3 and 4) and the point rail 20, the filler block being recessed, if desired, to accommodate the welding.

5 Thus an expansion joint is provided which is rugged in construction and which will stand up for long periods of service. The expansion joint is capable of general application at any point where there is likely to be considerable 10 creepage of the rail. For example, the expansion joint may be used at the ends of long bridges or at the ends of long sections of welded track to take care of the accumulated expansion and contraction which would ordinarily be 15 spread along the length of the track by the ordinary individual rail joints between rails. The expansion joint permits the independent movement of the rail point 20 and of the stock rail 26, together with the rails attached thereto, 20 in either direction relative to the road bed. For example, the expansion joint will accommodate movement of either rail, or both, of sixteen inches or more in either direction.

The auxiliary braces 47, 49 and 50, main 25 brace 48, tip brace 33, point rail 20, filler blocks 35 and 38 and the recessed seat 37, all form in effect a guideway for the stock rail. This guideway holds the straight portion of the stock rail with its gauge line in line with the gauge line 30 of the point rail and bends or deflects the end of the stock rail from its normal straight condition. As the point rail and stock rail move relatively to each other, the stock rail slides longitudinally in the above-mentioned guideway, 35 causing parts of the stock rail to straighten out as they move to the right of the tip brace 33 (Fig. 1), and to deflect laterally as they move to the left of the tip brace. Thus the expansion joint has a constant track gauge throughout the 40 length thereof and provides constant support between the point and stock rails, irrespective of movement of the rails longitudinally. In other words, movement of the rails does not produce any gap nor any change in track gauge.

45 The expansion joint may be used in both rails of a railway track. If the track handles one-way traffic only, the expansion joints may be arranged so that both point rails trail the traffic, in which case no guard rails are necessary. In 50 this case, the expansion joints will be made in rights and lefts. If the track must handle traffic in both directions there is no particular advantage in using rights and lefts. In this case, the expansion joints may be spaced along the 55 length of the track with the point rails in opposite directions and with a guard rail opposite each point to hold the wheel flanges away from the points.

While certain novel features of the invention 60 have been disclosed and are pointed out in the annexed claims, it will be understood that various omissions, substitutions and changes may be made by those skilled in the art without departing from the spirit of the invention.

65 What is claimed is:

1. In an expansion rail joint, a fixed support, a slidably support thereon, a point rail affixed to said slidably support, a guideway affixed to said slidably support and having a straight portion 70 in line with said point rail and a deflected portion extending along the outer side of said point rail, and a laterally flexible rail longitudinally slidably in said guideway.
2. In an expansion rail joint, a fixed support, 75

5 a slidable support thereon, a point rail affixed to said slidable support, a guideway affixed to said slidable support and having a straight portion in line with said point rail and a deflected portion extending along the outer side of said point rail, and a laterally flexible rail longitudinally slidable in said guideway, said guideway including braces and parts attached to said point rail overlying the base flange of said flexible rail.

10 3. In a track structure, a fixed support, a slidable support thereon, a point rail on said slidable support, a stock rail on said slidable support and having a straight portion in line with said point rail and a deflected portion extending along the outer side of said point rail, one of said rails being slidable lengthwise of itself with respect to said sliding support, the other of said rails being fixed lengthwise of 15 itself on said support.

15 4. In combination, a fixed plate, a sliding plate resting on said fixed plate, a point rail fixedly mounted in said sliding plate, a filler block secured to the outer side of said point rail, the outer side of said filler block and of said point rail describing a gradual curve, a flexible rail resting on said sliding plate and having a laterally flexible end overlapping and fitting said point rail, braces secured to said sliding 20 plate and slidably fitting the opposite sides of the body of said flexible rail, an end brace secured to said sliding plate and to the inner side of said point rail, and an end brace opposite said filler block secured to said sliding plate and 25 slidably fitting said flexible rail.

30 5. In an expansion rail joint, a fixed plate, a sliding plate resting on said fixed plate and having a depressed seat, a point rail fixedly mounted in said seat, a tip brace at the tip of said point rail, an auxiliary brace spaced from said tip brace, said tip brace and said auxiliary brace being secured to said sliding plate and to said point rail, a filler block secured to the outer side of said point rail, the outer side of said 35 filler block and of said point rail describing a gradual curve, a flexible rail resting in said seat and having a laterally flexible end overlapping and fitting said point rail, oppositely disposed braces secured to said sliding plate and slidably fitting the body of said flexible rail, a main brace secured to said sliding plate slidably fitting said tip brace, said tip brace slidably fitting said flexible rail, and an end brace opposite said filler block secured 40 to said sliding plate and slidably fitting said flexible rail.

45 6. In an expansion rail joint, a fixed plate overlying a considerable number of ties and having opposed holdown ways, a sliding plate in

5 said ways resting on said fixed plate and having a depressed seat, a point rail fixedly mounted in said seat, a tip brace at the tip of said point rail having offset first and second portions, auxiliary braces spaced from said tip brace, said tip brace and said auxiliary braces being secured to said sliding plate, said first offset portion and said auxiliary braces being secured to said point rail, filler blocks secured to the outer side of said point rail, the outer sides of said filler blocks and of said point rail describing a gradual curve, a stock rail resting in said seat and having a laterally flexible end overlapping said point rail, said flexible end having the inner side of its head undercut and the inner side of its 10 base flange cut away to fit the point rail, oppositely disposed braces secured to said sliding plate and slidably fitting the body of said stock rail, a main brace secured to said sliding plate slidably fitting said stock rail opposite said tip 15 brace, said second offset portion slidably fitting said stock rail, and an end brace opposite said filler blocks secured to said sliding plate and slidably fitting said stock rail.

20 7. In an expansion rail joint, a large plate, a point rail fixedly mounted on said plate, a filler block secured to the outer side of said point rail, a flexible rail resting on said plate and having a flexible end overlapping and fitting said point rail and filler block, and braces secured to 25 said plate and slidably fitting the opposite sides of said flexible rail.

30 8. In an expansion rail joint, a supporting member having a guideway, a point rail fixedly mounted on said supporting member, a flexible rail slidable in said guideway and having a flexible end overlapping said point rail, said guideway extending a considerable distance on opposite sides of the tip of said point rail to hold said point rail and flexible rail in proper relation.

35 9. In an expansion rail joint, a plate having a depressed seat, a point rail fixedly mounted in said seat, a tip brace at the tip of said point rail, an auxiliary brace spaced from said tip 40 brace, said tip brace and said auxiliary brace being secured to said plate and to said point rail, a filler block secured to the outer side of said point rail, a flexible rail resting in said seat and having a laterally flexible end overlapping and fitting said point rail, oppositely disposed 45 braces secured to said plate and slidably fitting the body of said flexible rail, a main brace secured to said plate slidably fitting said flexible rail opposite said tip brace, said tip brace slidably fitting said flexible rail, and an end brace opposite said filler block secured to said plate and 50 slidably fitting said flexible rail.

55 HERBERT S. CLARKE.
